UNITED STATES PATENT OFFICE.

ALBERT M. PIGEON, OF NORRISTOWN, PENNSYLVANIA.

PRESSING AND SUSTAINING MEANS FOR SPRING-BEARD NEEDLES.

1,403,103.

Specification of Letters Patent. Patented Jan. 10, 1922.

Application filed December 6, 1919. Serial No. 343,078.

To all whom it may concern:

Be it known that I, ALBERT M. PIGEON, a citizen of the United States, residing at Norristown, in the county of Montgomery and State of Pennsylvania, have invented 5 certain new and useful Improvements in Pressing and Sustaining Means for Spring-Beard Needles, whereof the following is a specification, reference being had to the accompanying drawings.

The invention relates to knitting machines, and more especially to knitters in which spring beard needles are employed such, for example, as the type shown and 15 described in the U. S. patent, Serial No. 1,266,045, granted to me under date of May 14, 1918.

Heretofore, in the operation of such machines considerable trouble has been experienced through the fracture of the needle beards owing to lateral flexure under pull occasioned by enlargements, knots or other irregularities in the yarn. If the beards were not directly broken by the lateral strain 20 thus produced, fracture was sure to result from retraction of the needles during stitch formation, either by the engagement of the deflected beards with the top of the needle cylinder adjacent the needle grooves, or by 25 the hooking of the beards about the associated web holders. In order to obviate this difficulty, I have provided means for 30 positively sustaining the beards of the needles against such lateral flexure at the critical period, i. e., at the time when the tips 35 of the descending needle beards are passing over the yarns during the feeding of the latter.

A further difficulty heretofore met with 40 in the employment of spring beard needles, was to insure the feeding of the yarn positively beneath the tips of the beards. This obstacle I overcome by preventing bowing 45 of the yarn away from the needle shanks during feeding, so that engagement beneath 50 the beards is positively assured during retraction of the needles in stitch formation.

In the accompanying drawings, Fig. I, 55 is a fragmentary sectional view through the needle cylinder of a circular knitter, and its appendages, conveniently illustrating my invention.

Fig. II, is a perspective view of one of the improved beard pressers which I employ.

Fig. III, is a detail sectional view on an enlarged scale showing the relative positions

of the presser, yarn, and the end or tip of the needle beard at the time of passing the yarn prior to the drawing of a loop.

Fig. IV, is a diagrammatic plan view 60 showing the relative positions of the needle, the co-operative beard presser, and the associated web holder.

Referring first to Fig. I, it will be noted 65 that the general characteristics of the structure are identical with those of Figs. I and III, of the patents cited. This structure includes a needle cylinder herein indicated by the numeral 1, and shown as formed with the usual longitudinal grooves 2, within 70 which are slidably supported the needles 3. Said needles are of a standard type having 75 the spring beards indicated at 4.

Mounted in the groove 2 with each needle 80 1 is a beard presser 5, having near its lower end a notch 6, which is engaged by a spring band 7. This band is common to the entire 85 series of pressers, serving as a general and universal retainer and also preventing vertical movement of the pressers during the operation of the needles. The pressers 5 are adapted to be rocked about the fulcrum afforded by a curved bulge 8 thereon, under the actuation of the cam 9, operative against their tops, (see Fig. III). Each of said 90 pressers 5 is formed with an inclined upper cam surface or edge 10, adapted to engage the needle beard to gradually depress the same when the needle is drawn downwardly to form the stitch. Adjacent this cam edge, 95 at one side, the presser has an extended offset projection 11 (preferably integral) upward and forward from the inclined surface 10 to a point substantially just above the lower end of said surface 10 and substantially at (i. e., as shown, a little above) the level of the upper end of said surface 10. This projection 11 has the configuration clearly shown in Figs. I, II and III, and is adapted, primarily, to sustain or steady the 100 beard against lateral flexure as will be presently explained. The tip of the extension is rounded as at 12, for a purpose later set forth herein.

Associated with the needles are individual web holders 13, which are mounted for horizontal reciprocation in appropriate slots formed in a dial ring 14, attached to the top of the needle cylinder 1. Said web holders 105 are of the usual type, and are actuated by 110 means of a cam ring 15, in a manner clearly set forth in the patent referred to.

In operation, the yarn Y (see Figs. I and IV) is laid against the shanks of the needles, and the latter are retracted or drawn downward to form stitches, under 5 the control of cams of any approved type (not shown). During their descent, the tips of the needle beards 4 pass over the yarn, and are immediately thereafter depressed by engagement with the cam inclines 10, of 10 the pressers 5. Were it not for the support afforded the beard 4 by the projection 11 about at and after its first engagement with the yarn Y, any knot or other enlargement K in the yarn (Fig. IV) would act (owing 15 to the relative motion of the yarn indicated by the arrow) to deflect the beard 4 laterally and hook it about the adjacent web holder, and consequently break it during further retraction of the needle.

20 Referring now to Fig. III, it will be seen that the rounded tip 12, of the projection 11, of the beard presser facilitates the passage of the yarn behind the same during feeding. As a consequence the yarn subsequently reeves 25 into the interspace between the presser 5 and the needle shank, and is thus prevented from bowing outwardly and away from said shank during the descent of the needle to form a fabric loop, so that positive feeding beneath the beard 4 is assured.

30

From the above it will be seen that by the present invention I have overcome two of the most serious drawbacks (previously referred to) which heretofore prevented the more general adaptation of spring beard needles to knitting machines more especially designed for fine gauge work.

While I have herein shown and described 40 my invention as being applied to a circular knitting machine, it is to be understood that I do not wish to be so limited since it may be incorporated with equal advantages in machines of the straight or bar type.

Having thus described my invention, I 45 claim:

1. In a knitting machine, the combination 50 of a spring beard needle, means for depressing the needle beard, and means for sustaining the beard against lateral flexure by the yarn at and after its first engagement with the yarn, as well as during depression by said depressing means.

2. In a knitting machine, the combination of a spring beard needle, means for depressing the needle beard, and means for 55 guiding the yarn against the needle shank during feeding and sustaining the needle beard against lateral flexure by the yarn at and after its first engagement with the yarn, as well as during depression by said de- 60 pressing means.

3. A spring beard needle presser having an inclined beard-depressing upper surface, and an extended lateral beard support projecting upward and forward from said surface, at one side thereof, for sustaining the needle beard against lateral flexure by the 65 yarn at and after its first engagement with the yarn.

4. A spring beard needle presser having 70 an inclined beard-depressing upper surface, and a lateral beard support projecting upward and forward from said surface, at one side thereof, to a point substantially just above the lower end of said surface and substantially at the level of its upper end, for 75 sustaining the needle beard against lateral flexure by the yarn during feeding.

5. A spring beard needle presser having an inclined beard-depressing upper surface, 80 and a lateral beard support projecting upward and forward from said surface, at one side thereof, to a rounded tip substantially just above the lower end of said surface and above the level of its upper end, for 85 guiding the yarn behind the presser and sustaining the needle beard against lateral flexure during feeding.

6. A spring beard needle presser having 90 an inclined beard-depressing upper surface, and an extended laterally offset beard support projecting upward and forward from said surface, at one side thereof, for sustaining the needle beard against lateral flexure by the yarn at and after its first en- 95 gagement therewith.

In testimony whereof I have hereunto signed my name at Philadelphia, Pennsylvania, this fourth day of December, 1919.

ALBERT M. PIGEON.
